UNITED STATES PATENT OFFICE.

LE GRAND PARISH, OF MOUNTAINVIEW, NEW JERSEY, ASSIGNOR TO AMERICAN ARCH COMPANY, OF NEW YORK, N. Y., A CORPORATION OF DELAWARE.

PROTECTION FOR ARCH-TUBES.

1,229,377.

Specification of Letters Patent. Patented June 12, 1917.

Application filed January 8, 1916. Serial No. 71,060.

To all whom it may concern:

Be it known that I, LE GRAND PARISH, a citizen of the United States, and a resident of Mountainview, Passaic county, New Jersey, have invented certain new and useful Improvements in the Protection for Arch-Tubes, of which the following is a specification.

My invention relates to improvements in refractory arches or baffles for locomotive boiler furnaces and has special reference to improvements in the mounting of refractory arch bricks upon the water-circulating arch tubes of such boilers.

The subject-matter of this application is a modification of that which is shown and described in my application, Serial No. 71,061, filed January 8, 1916, entitled Locomotive fire box arches.

The material of which arch bricks are made is highly abrasive; so much so, that as the metal arch tubes expand, contract and warp during usage, the coincident movement of the refractory bricks upon the arch tubes wears away the portions of the tubes upon which the bricks rest. Not infrequently arch tubes are allowed to remain in the fireboxes until from these causes they are worn so thin as to burst under boiler pressure or collapse under the weight of the arch bricks. Doubtless the danger could be avoided by frequent inspection and replacement of the tubes; but the difficulty is that the tubes cannot be inspected without removing the arch bricks, and the amount of time and labor needed for that operation is such that it has become the practice to postpone inspection of the tops of the arch tubes until the time of the removal of the bricks or until some clearly apparent fault in an arch tube makes the operation necessary.

The objects of my invention are, to avoid these dangers;—to make the frequent inspection of arch tubes unnecessary;—to avoid the heavy expense of tube replacements due to the arch brick wear;—and to prolong the life of arch tubes.

I accomplish these objects by interposing a relatively permanent, but easily removable, wearing strip between each arch tube and every brick which rests upon it. I prefer that the wearing strips shall be composed of metal clips clasped upon the arch tubes and furnishing bearings upon which

the bricks rest, and whereby the bricks are raised out of wearing contact with the tubes. My invention also consists in novel details of construction, whereby the clips are made to perform the additional function of positively holding the bricks upon the tubes until they are more or less intimately united by heat and slag deposits.

My invention will be readily understood on reference to the accompanying drawings that form part of this specification, and in which:—Figure 1 is a vertical longitudinal section of a locomotive firebox containing a front arch embodying my invention;—Fig. 2 is an enlarged detail of the arch;—Fig. 3 is an enlarged cross-section of the arch, on a plane perpendicular to the arch tubes;—Fig. 4 is a similar view showing bricks of a different type and wearing clips of a modified form;—Fig. 5 illustrates a still further modification;—Fig. 6 is a detail plan view illustrating the manner in which the wearing strips or clips are placed to provide three-point bearings for the arch bricks; and, Fig. 7 is a longitudinal section similar to Fig. 2, but showing the clips disposed in another way.

In Fig. 1 of the drawings, 2 represents the flue sheet of a locomotive boiler furnace or firebox. Typical side sheets, 3, and a typical crown sheet, 4, and a typical rear sheet, 5, are shown. The forwardly and downwardly inclined water-circulating metal arch tubes, 6, may be of any desired number, shape and size. They are usually spaced at equal distances and ordinarily are parallel.

The marginal arch bricks, 7, are supported by the outer tubes, 6, and the side sheets of the firebox. Intermediate arch bricks, 8, close the spaces between the several arch tubes. The wearing or protecting strips above referred to are placed on the tubes, and the several bricks rest thereon instead of directly upon the tubes. As best shown, in Figs. 3, 4, 5, and 6, the arch bricks are of the sectional type, characterized by socketed ends shaped to fit the arch tubes.

In many instances the intermediate arch bricks will be found in the form shown in Fig. 3, that is, characterized by end sockets which provide inclined ends, 9. In other instances the bricks will be found in the form shown in Fig. 4, having one curved socket, 10, and one inclined end, 11. And

in still other instances the bricks will be found provided with curved sockets, 12, at both ends, as shown in Fig. 5. My invention is adapted for use with all forms of sectional arch bricks, whatever the shape of the bearing surface that the brick presents to the supporting arch tubes.

In all forms of tube-supported sectional arches, the expansion and contraction of the firebox side sheets and of the arch tubes causes considerable movement between the arch tubes and the bricks which they support. This movement results in the objectionable wearing away of the arch tubes at the places where the arch bricks bear upon them. To obviate this difficulty I place upon the tubes, before setting the bricks thereon, a plurality of wearing strips in the form of metal clips which are spaced apart upon respective tubes and provide bearings for the bricks, in lieu of the arch tubes.

Several of these wear-receiving clips are provided upon each arch tube, their number and arrangement varying with the number and positions of the arch bricks. I make the clips in several forms. Thus, as shown in Fig. 3, the clip, *a*, is of substantially circular form, but split or open so that it may be forced into position over the tube. Such clips are also shown in Figs. 1, 2 and 7, in which it will be seen that the positions of the clips upon the tubes, 6, may be varied as desired according to the kind of bearings best suited to the bricks and tubes with which they are to be used. As indicated in Fig. 2, a single clip, *a*, in each case may provide the bearing or wearing-support for the abutting sides of two arch bricks in the same longitudinal row; or, as shown in Fig. 7, the clips may be more numerous to provide each brick-end with two separate bearings. Frequently the water tubes are not in exact parallelism and in such cases the bricks may be most securely lodged upon the tubes by limiting them to three points of bearing thereon. My novel wear-preventing strips or clips lend themselves admirably to the accomplishment of this purpose, as shown in Fig. 6.

In order that the weight imposed upon the arch tubes shall not be excessive, arch bricks are made as light as consistent with the work to be performed by them. Thus it happens that when arch bricks are first placed upon the arch tubes and before they are in a measure sealed together by fusion and slag, they are apt to be lifted off the tubes by the strong suction between the grate and the flues of the firebox. To avoid this difficulty I shape the wearing clips in such manner that they act as locking devices to temporarily secure or anchor the arch bricks upon the tubes until such time as they are anchored thereto by the action of the fire. I accomplish this without sacri-

ficing the wear-resisting function of the clips.

There are two forms of the clips which best perform the double function of providing bearings for the bricks and also anchoring the bricks. One form is shown in Fig. 4 and a second form in Fig. 5. They are alike, in that both have T-shaped heads which overlap the tops of the brick ends and serve to prevent the lifting of the bricks from the tubes. The clip, *b*, shown in Fig. 4 is characterized by a T-head or anchor portion, *b'*, formed integrally by the middle part of the strip of metal composing the clip. The clip, *c*, of Fig. 5 is characterized by a two-part or divided T-head, *c'*, formed by the outwardly-bent ends of the metal strip. Obviously, both forms of the anchoring clip, when placed in position between the ends of two bricks, effectively secure the same to the supporting tube. The necks or stems, *d*, of the anchoring strips are thinner or narrower than the normal spaces between the adjacent ends of the bricks and therefore the clips do not prevent endwise movement of the bricks.

The portion of the metal clip which is tightly seated against the outer surface of the water-cooled tube is cooled and protected thereby. The upwardly projecting anchor-portion of the clip is not so well protected and may ultimately burn away, but this is not objectionable, for by the time the anchor-portion burns away the bricks are so loaded and sealed with slag that the metal anchor is no longer required. Obviously, the burning away of the anchor projection does not disturb the wear-resisting bearing portion of the clip in its relation to the tube or the brick.

Anchoring clips of the kind shown in Figs. 4 and 5 may be distributed in the three-point bearing relation disclosed in Fig. 6, quite as well as can the clips of the simpler form shown in Fig. 3.

Various modifications of my invention will readily suggest themselves to those skilled in the art, and, except as stated in the appended claims, I do not limit my invention to the specific structures herein shown and described.

Having thus described my invention, I claim as new and desire to secure by Letters Patent:—

1. A locomotive firebox and contained group of water-circulating arch tubes, in combination with refractory arch bricks supported by and between said tubes, and metal wearing clips spaced upon said tubes and providing three-point bearings for the bricks.

2. A locomotive firebox and contained group of water-circulating arch tubes, in combination with refractory arch bricks supported by and between said tubes, metal

wearing clips clasped upon said tubes in spaced relations and providing bearings for said bricks and thus relieving the tubes from the wear of the bricks.

5 3. A locomotive firebox and contained group of water circulating arch tubes, in combination with refractory arch bricks supported by and between said tubes, metal wearing clips spaced upon said tubes and

providing bearings thereon for said bricks, 10 and said clips being provided with brick anchoring projections upon their tops, which engage the bricks and prevent the lifting thereof from the tubes.

In testimony whereof, I have hereunto 15 set my hand this 28th day of December, 1915.

LE GRAND PARISH.
